UNITED STATES PATENT OFFICE.

OLIVER CROSBY, OF ST. PAUL, MINNESOTA.

SUPPLEMENTARY TRACK.

SPECIFICATION forming part of Letters Patent No. 650,927, dated June 5, 1900.

Application filed August 26, 1898. Serial No. 689,619. (No model.)

To all whom it may concern:

Be it known that I, OLIVER CROSBY, a citizen of the United States, residing at St. Paul, Ramsey county, Minnesota, have invented an improvement in Supplementary Tracks, of which the following is a specification.

My invention relates to improvements in supplementary tracks; and it consists particularly in the construction and arrangement of the tracks, as hereinafter described.

In the accompanying drawings, forming part of this specification, Figure 1 is a plan view showing my construction and arrangement of rails laid upon flat-cars. Fig. 2 is an end view thereof, and Fig. 3 is a side elevation.

In the drawings, A represents a flat-car, and 2 the wheels thereof, running upon the rails 3. Arranged upon the top of the flat-cars is 20 my supplementary track. This consists of a series of sections of overlapping rails 4 and 5, connected by tie-rod 6 and secured to ties 7, resting transversely upon the flat-cars. The distance between the rails 5, as will be seen, 25 is less than between the rails 4, so that the rails may overlap, as shown in Fig. 1.

8 are the truck-wheels, which are adapted to run upon rails 4 and 5 and which carry a derrick or other desired apparatus. (Not 30 shown.) The wheels 8 are formed with a central flange 9, so that when traveling upon the rails 4 the outer edge of the wheel will be the bearing-surface and when traveling upon the rails 5 the inner edge of the wheel will be 35 the bearing-surface.

In use a supplementary track consisting of two or more sections is laid upon the flat-cars, as shown in Fig. 1. As a derrick or other apparatus is transported along the supplemen-

tary track the rear section may be lifted and 40 placed in connection with the forward section. A series of two sections may thus be used to constitute the supplementary track, regardless of the length of the train of flat-cars. By having the track formed of inde- 45 pendent sections it will also be evident that the track will easily adapt itself to the movement of the flat-cars and to the angles assumed by the cars passing around curves.

While the track is shown laid upon flat- 50 cars, it may be laid upon canal-boats, &c.

I claim—

1. A track consisting of a series of independent portable track-sections, said sections being out of line with each other, and the 55 ends of the rails of each section overlapping the ends of both rails of the next section.

2. A track consisting of a series of independent portable track-sections, the gage of each alternate section being narrower than 60 that of the adjacent sections, whereby the rails of the narrower section fit between those of the wider.

3. A track consisting of a series of independent portable track-sections, the rails of 65 each section being suitably secured together, and the gage of each alternate section being narrower or broader than that of the adjacent sections, so that both rails of the narrow section will stand between the rails of the 70 wider.

In testimony whereof I affix my signature in the presence of two witnesses.

OLIVER CROSBY.
